TREATMENT OF STOCKINGS AND OTHER
KNITTED ARTICLES

Luis Heldmaier, Leicester, England

Application January 15, 1946, Serial No. 641,251
In Great Britain January 26, 1945

4 Claims. (Cl. 223—76)

1

This invention relates to improvements in the treatment of stockings and other shaped textile articles, more particularly articles made of nylon or a similar polyamide type of synthetic product, hereinafter referred to, for convenience, as "Nylon stockings." The invention is also, however, applicable to the treatment of shaped textile articles made of cellulose acetate and pure silk, as will be explained hereinafter.

It is well recognised that for the satisfactory production of nylon stockings it is necessary to subject the stockings to a heat and steam treatment in order to plasticise the material, this treatment being known in the trade as "pre-boarding." In the past, pre-boarding of nylon stockings has been carried out by mounting the stockings on forms and keeping them, whilst still on the forms, in a stationary steam chamber. This, however, is a slow process and it has been proposed in my co-pending patent application No. 622,019 filed October 12, 1945, now abandoned, to carry out this pre-boarding treatment as a continuous process, the forms to receive the stockings being carried by an endless conveyor which is adapted to take the stockings on the forms, after suitable preliminary treatment if desired, through a pre-boarding chamber in which they are subjected to the action of live steam and heat.

The chief object of the present invention is to provide a modification of, or improvement on, the process of pre-boarding or plasticising shaped textile articles described in our said co-pending patent application, more particularly in respect to the manner of producing the additional heat required and of easily controlling the same.

The apparatus for pre-boarding or plasticising shaped textile articles, more particularly nylon stockings according to the present invention, includes an endless conveyor carrying forms for the reception of the shaped textile articles and a pre-boarding or plasticising chamber through which the articles on the forms are passed due to movement of the conveyor, and is characterised by the provision of means for supplying live steam to the pre-boarding or plasticising chamber and of one or more gas heaters for supplementing the heat of the live steam supplied to the pre-boarding or plasticising chamber.

Preferably a fan is provided to circulate the live steam and hot air through the pre-boarding or plasticising chamber, conveniently in a substantially closed circuit, as hereinafter explained.

In order that this invention may be the more clearly understood and readily carried into effect, reference may be made to the accompanying drawings, in which:

Figure 1 illustrates diagrammatically the lay

2

out of the complete plant for plasticising and finishing shaped textile articles according to the present invention.

Figure 2 is a longitudinal vertical section through the gas heated plasticising chamber, and

Figure 3 is a plan view of the same.

Referring now to Figure 1 of the accompanying drawings, the plant therein illustrated is, in general, similar to that used for the continuous finishing of stockings, and comprises an endless conveyor chain 10 carrying at spaced intervals the forms (not shown) over which the stockings or other articles are placed at the loading position 11. The nylon stockings having been placed over the forms (and stretched over the same, if desired), are first passed through a spray box 12 in which water, hot or cold, is sprayed on to both sides of the stockings or the like, and are then allowed to travel for some distance, as indicated at 13, to allow the water to impregnate the stockings or the like thoroughly, and are then passed through a further spray box 14 in which they are sprayed on both sides with hot water. After leaving the spray box 14 the stockings or the like on the forms are passed between a pair of sponge rubber or similar rollers 15 which equalise the water sprayed on over the whole of the stockings or the like. After emerging from between the rollers 15, the stockings or the like, still on the forms, are passed into a gas heated plasticising chamber 16, the construction and arrangement of which will be described more fully hereinafter.

After emerging from the plasticising chamber, the stockings are passed through a drying chamber 20 in which they are finished or conditioned and are returned to the unloading point 21 where the stockings or the like are removed and the forms pass on to the adjacent loading point 11. The stockings or the like may be dried in the drying chamber 20 by means of a stream of hot air, by means of electrically or steam heated panels in the walls of the chamber, by means of the apparatus described in British Patent specification No. 458,550, or in any other suitable way.

Turning now to the plasticising chamber 16 and referring to Figures 2 and 3, this comprises an outer metal or like casing 30 which need only be quite narrow, lagged, as at 31, with a suitable lagging, for example silicate cotton, to prevent the escape of heat. A narrow vertical opening 32 is provided at each end for the entrance and exit of the stockings on the forms, gap adjusting plates or rollers 33 being provided on either side of the openings 32 to prevent as far as

possible the escape of the steam and hot air within the plasticising chamber 16.

Mounted on top of the outer casing 30 is an electric motor 34 driving a fan 35 which is adapted to force hot air along a horizontal conduit 36 extending towards the front or entrance end of the chamber. The front end of the conduit 36 communicating with two vertical channels 37, one on each side of the opening 32, feeds hot air through the rear faces of these channels 37 which are perforated. At the further end of the plasticising chamber 16 there is a similar arrangement, the air and steam being sucked through perforations in the front walls of two vertical channels 38, one on each side of the exit gap 32. At their upper ends, the vertical channels 38 communicate with a horizontal conduit 39 similar to the conduit 36. Before reaching the fan, however, the steam and air are passed through a heater 40 in which they are raised to the desired heat by means of the flame from a gas injector burner 41.

Steam is injected into the plasticising chamber by means of sprays, one of which is shown at 50.

The hot air and live steam is thus caused to flow in a closed circuit and the stockings or the like will be plasticised as they travel through the chamber 16.

Furthermore, with a view to reducing the time taken to raise the forms to the desired temperature within the chamber 16, which time is, of course, wasted from the point of view of plasticising the stockings or the like since the forms are travelling continuously through the chamber, the forms may be pre-heated by passing them through preheaters 60 before they enter the chamber in any conventional way.

Gas-operated heaters have many advantages over infra-red lamps, for example they are less expensive in initial cost, cheaper to run and far less complicated. Furthermore, in the atmosphere of live steam in which the heaters must operate according to the present invention, they are less liable to breakdown since a gas-operated heater is practically immune from damage due to moisture, whereas electric infra-red lamps are not.

Gas heating also has the advantage that it is very simple to adjust and control the temperature so that the plasticising may be carried out at the most efficient temperature.

Although the present invention is more particularly concerned with the plasticising of stockings and other articles made of nylon or a similar polyamide type of synthetic resin, the process may usefully be applied to the treatment of articles made of cellulose acetate and other products, more particularly articles made of animal products, notably pure silk, the articles so treated having improved qualities of texture, durability and appearance.

I claim:

1. Apparatus for pre-boarding shaped textile articles, more particularly nylon stockings, comprising an endless conveyor carrying forms for the reception of the shaped textile articles, a pre-boarding chamber through which the articles on the forms are passed due to movement of the conveyor, means for supplying live steam to the pre-boarding chamber, at least one gas heater for supplementing the heat of the live steam supplied to said chamber, and an air conduit disposed along the top of said chamber and communicating at each end with a pair of ver-

tically disposed air channels arranged one on each side of the entrance and exit apertures of the pre-boarding chamber, and a fan adapted to circulate the steam and hot air of the chamber in a substantially closed circuit through said air conduit.

2. Apparatus for pre-boarding shaped textile articles, more particularly nylon stockings, comprising an endless conveyor carrying forms for the reception of the shaped textile articles, a pre-boarding chamber through which the articles on the forms are passed due to movement of the conveyor, means for supplying live steam to the pre-boarding chamber, at least one gas heater for supplementing the heat of the live steam supplied to said chamber, a conduit for conveying heated air, said conduit including a horizontal portion disposed along the top of said pre-boarding chamber and communicating vertically-disposed portions at each end of said pre-boarding chamber, said vertically-disposed portions being in communication with the interior of said chamber, and a fan adapted to circulate the steam and hot air of said pre-boarding chamber in a substantially closed circuit through said air conduit.

3. Apparatus for pre-boarding shaped textile articles, more particularly nylon stockings, comprising an endless conveyor carrying forms for the reception of the shaped textile articles, a pre-boarding chamber through which the articles on the forms are passed due to movement of the conveyor, means for supplying live steam to the pre-boarding chamber, at least one gas heater for supplementing the heat of the live steam supplied to said chamber, an air conduit for conveying heated air, said conduit including a horizontally extending portion disposed along the top of said chamber and communicating vertically-disposed portions at each end of said pre-boarding chamber, the inner surfaces of said vertically-disposed portions being in communication with the interior of said chamber, and a fan adapted to circulate the steam and hot air of the chamber in a substantially closed circuit through said air conduit.

4. The apparatus as defined in claim 2, which includes an additional heating means, said additional heating means being adapted to pre-heat said forms on said endless conveyor prior to introduction of said heated forms into said pre-boarding chamber.

LUIS HELDMAIER.
